PLATTER OR SIMILAR ARTICLE

Toni Olga Muench, East Liverpool, Ohio, assignor to Fisher, Bruce & Company, Philadelphia, Pa., a corporation of Pennsylvania

Application August 10, 1954, Serial No. 31,804

Term of patent 7 years

(Cl. D44—10)

To all whom it may concern:

Be it known that I, Toni Olga Muench, a citizen of the United States, residing in East Liverpool, Columbian County and State of Ohio, have invented a new, original, and ornamental Design for Platter or Similar Article, of which the following is a specification, reference being had to the accompanying drawing, forming a part hereof.

Figure 1 is a top plan view of a platter or similar article showing my new design.

Figure 2 is a side elevational view of said platter or similar article.

I claim:

The ornamental design for platter or similar article, as shown.
